BUTTER DISH

Clara Virginia Eicholtz, Midland, Mich., Richard K. Fritsche, Fort Thomas, Ky., James K. Heidrich, Cincinnati, Ohio, and Edgar F. Trombly, Grosse Pointe Farms, Mich., assignors, by mesne assignments, to The Miami Margarine Company, Cincinnati, Ohio, a corporation of Ohio

Filed Aug. 3, 1962, Ser. No. 71,157

Term of patent 14 years

(Cl. D44—5)

Fig. 2

Fig. 1

Fig. 3

Fig. 4

Fig. 5

Fig. 6

FIGURE 1 is an elevational view of a butter dish showing our new design;

FIGURE 2 is a top plan view thereof;

FIGURE 3 is an isometric view thereof;

FIGURE 4 is a cross-sectional view thereof, taken along reference line 4—4 of FIGURE 2;

FIGURE 5 is a cross-sectional view thereof, taken along reference line 5—5 of FIGURE 2; and

FIGURE 6 is an enlarged fragmentary cross-sectional view thereof, taken along reference line 6—6 of FIGURE 3.

We claim:

The ornamental design for a butter dish, as shown.
